UNITED STATES PATENT OFFICE.

FREDERICK D. SMENNEE, OF FORT WAYNE, INDIANA.

FIRE-ALARM.

981,020.

Specification of Letters Patent. Patented Jan. 10, 1911.

Application filed September 9, 1908. Serial No. 452,204.

To all whom it may concern:

Be it known that I, FREDERICK D. SMENNEE, a citizen of the United States of America, and resident of Fort Wayne, in the county of Allen and State of Indiana, have invented certain new and useful Improvements in Fire-Alarms, of which the following is a specification.

This invention relates to improvements in fire alarms, and the object thereof is to afford apparatus of the class used for detecting the presence of fire, that will be delicately sensitive to a flame, and at the same time exert sufficient force when set in operation to actuate alarms requiring more or less mechanical energy to actuate. This object is accomplished by the construction illustrated in the accompanying drawing which shows an elevation of the mechanism composing the apparatus together with its accessories, parts thereof being shown in vertical section.

Referring now to the drawing, 1 is a case containing the actuating mechanism. 2 and 3 are triggers which are pivoted respectively as shown at 2' and 3' so as to tilt thereon. The trigger 2 engages and holds in suspension a weighted arm 4 that swings on a pivot 5. When released by the trigger 2 the arm is adapted to gravitate and strike another trigger 6 that detains in suspension another weighted arm 7. When released by its trigger, the arm 7 is adapted to gravitate and strike a trigger 9 that in turn detains in suspension a weighted arm 10, and the latter is pivoted at 11 the same as the arm 7 is at 8 and arm 4 is at 5. The arm 10 when released by the trigger 9 is adapted to gravitate and strike the trigger 12. The blow of the respective arms against the corresponding triggers beneath is such as to move the latter into lowermost position and cause the release of the parts held in suspension thereby. The several weighted arms are of different sizes and consequently of different weight, the first arm 4 being the lightest; the succeeding arm 7 being heavier than the first, and the next arm 10 being still heavier, thus the force of the succeeding blows of the weighted arms increases proportionately.

The trigger 12 engages and holds in suspension a weighted trigger 13 that in turn engages and holds in a similar manner a weighted lever 14. When the trigger 12 is actuated by the arm 10, the weighted trigger 13 is released and the latter thereby releases

the lever 14. The lever 14 has a blade 15 that in connection with the terminal plates 16 forms a switch for completing the electrical circuit of the wires 17, it being understood that the latter are to be suitably connected with a source of electrical energy in the usual manner. The lever 14 has also an arm 18 beneath its pivotal support 19, and the arm 18 is adapted to operate the valve 20 which controls a whistle 21. The triggers 6, 9, 12 and 13 are each provided with a stop 22 to limit their respective movements, and the weighted arms are also likewise provided with stops 23 for a similar purpose.

24 is a disk mounted on a pivot 25 and is provided with a switch arm 26, the latter adapted to engage severally with opposite electrical contacts 27 and 28, respectively, and the arm 26 has electrical connection with one pole of a battery 29 by means of a wire 30. The disk 24 has a pivoted link 31, at the outer end of which is attached a pendent weight 32 and also an upwardly extending strip 33 which connects with the trigger 3 by means of a hook 34 attached to the latter and which extends through the end of the strip. When in connection with the trigger the strip holds the link at such an angle that the effect of the weight 32 is to hold the switch arm 26 into contact with the terminal 27, and when the strip is released from the trigger 3 the weight 32 falls, and the disk is thereby caused to turn with a jerk which insures movement of the arm 26 from one terminal 27 to the other 28.

The electrical wires 17 are connected with lamps 35, the globes of which are colored red to indicate danger, and these lamps are intended to be placed at convenient locations for observation. Line wires 36 and 37 are intended to be strung through various parts of a building where fire is most likely to occur. In connection with these line wires are circuit-closers A and B which are so constructed as to form an electrical connection between the wires 36 and 37 after being subjected to fire. The circuit closer A is designed to be attached to the ceiling, and is the same in general as the circuit closer B, the latter being designed to be attached to a wall. In each circuit closer is a weighted lever 38 that has electrical connection with the line wire 37, and also a contact terminal 39 that has connection with the other wire 36. Each lever is adapted to connect with the corresponding contact terminal 39 when

released by the burning of its retaining cord 40 which is of combustible material. Springs 41, one for each lever, aid in moving the latter when released.

5 One line wire 36 is connected with the pole of the battery opposite that having the connection with the switch arm 26 above referred to; and the other line wire 37 has connections with one side of a motor 42, 10 and with one side of an electric bell 43. The side of the bell opposite that referred to has connection with the contact terminal 28, and the side of the motor opposite that referred to has connection with the contact terminal 15 27 by means of the wire 44.

A slack cord 45 is connected from the end of the trigger 2 to a pulley 46 on the motor, so that when the motor turns the trigger will release the arm 4. Another slack cord 20 47 connects the outer end of the trigger 3 with the cord 45 so that as the motor continues to revolve after the release of the arm 4, the trigger 3 will be drawn downward also and thus the strip 33 is released. When 25 the strip is released the arm 26 is thrown from contact with the terminal 27 and into connection with the terminal 28.

When the apparatus is set as shown, should the cord 40 of one of the circuit closers become burned, the line wires 36 and 37 30 would become electrically connected and consequently the motor and battery would be completely in circuit and the former would be driven by energy from the latter. The 35 movement of the motor first actuates the trigger 2 and subsequently the trigger 3, and the movement of the latter releases the strip 33 so that the switch 26 is shifted into contact with the terminal 28 with the result 40 that the motor is thrown out of circuit with the battery and the bell into circuit therewith. Thus it is understood that the burning of the cord 40 of any circuit closer on the line wires will result in the red lamps 45 being lighted; the whistle blown; and the bell rung, all signaling the presence of fire.

Having described my invention, what I claim as new and desire to secure by Letters Patent, is:—

1. In apparatus of the class described, a 50 series of weighted arms pivotally mounted in successive order one above the other, the weights of the respective arms being successively greater from the uppermost to the lowermost; a trigger for holding each of 55 said arms in normal detained position, each arm being adapted to actuate the trigger of the succeeding arm; a fire signal; a weighted lever for actuating the signal; a weighted trigger for holding said lever normally 60 from action; a trigger for holding the weighted trigger in normal position and being located beneath the lowermost of said weighted arms and adapted to be actuated thereby; and means in connection with the 65 trigger of the uppermost weighted arm, adapted to be controlled by heat, for actuating the trigger to release the weighted arm.

2. In apparatus of the class described, a 70 series of weighted arms pivotally mounted in successive order one above the other, the weights of the respective arms being successively greater from the uppermost to the lowermost; a corresponding series of triggers to hold the respective arms in their 75 uppermost positions a fire signal; a trigger to control the signal, located beneath the lowermost of said weighted arms and adapted to be actuated thereby; and means in connection with the trigger of the uppermost 80 weighted arm, adapted to be controlled by heat, for actuating the trigger to release the weighted arm the triggers of the lower arms being adapted to be actuated respectively by the movement of the next preceding arm. 85

In testimony whereof I affix my signature, in presence of two witnesses.

FREDERICK D. SMENNER.
